UNITED STATES PATENT OFFICE.

ISAAC JAY AND JAMES C. JAY, OF ARAPAHOE, NEBRASKA.

FEED-GRINDER.

SPECIFICATION forming part of Letters Patent No. 359,788, dated March 22, 1887.

Application filed June 3, 1886. Serial No. 204,023. (No model.)

To all whom it may concern:

Be it known that we, ISAAC JAY and JAMES C. JAY, both of Arapahoe, in the county of Furnas and State of Nebraska, have invented 5 a new and useful Improvement in Feed-Grinders, of which the following is a full, clear, and exact description.

Reference is to be had to the accompanying drawings, forming a part of this specification, 10 in which similar letters of reference indicate corresponding parts in all the figures.

Figure 1 is a side elevation of our improved feed-grinder shown as applied to a windmill, and the hopper being shown in section. Fig. 2 15 is a front elevation of the same, the hopper and its supporting-frame being removed. Fig. 3 is a sectional plan view of the same, taken through the line $\alpha\alpha$, Fig. 2.

The object of this invention is to provide 20 feed-grinders constructed in such a manner that they can be readily adjusted to grind different kinds of grain, and which shall be simple in construction and effective and reliable in operation.

25 The invention consists in the construction and combination of various parts of the feed-grinder, as will be hereinafter fully described and claimed.

We will describe our invention as being connected with and operated by a windmill-pitman, but do not limit ourselves to that arrangement, as it can be driven by any suitable power.

30 A represents the frame of an ordinary windmill, the operating mechanism of which is not shown, as there is nothing new in its construction and operation.

B is the pitman of the windmill, which, in the drawings, is represented as working a pump, 40 C, but which can be connected with any desired machinery.

D is a walking-beam, which is pivoted centrally to a post, E, the frame A, or other suitable support. One end of the walking-beam 45 D is connected with the pitman B, so that the said beam will be vibrated by the reciprocating movement of the said pitman. With the other end of the walking-beam D is connected the upper end of a pitman, F, the lower end of 50 which is pivoted to a plate, G, which moves

up and down in guides in the frame H of the feed-grinder. The plate G is dressed or burred upon its forward side to operate upon the grain.

To the frame H, in front of the plate G, is 55 journaled a cylinder, I, the face of which is dressed or burred to operate upon the grain. The face of the cylinder I is preferably dressed in three sections, the dressings of the three sections being of different degrees of fineness, 60 to adapt the said cylinder to be adjusted to operate upon different kinds of grain. The journals of the cylinder I project, and to them are secured, by set-screws or other suitable means, crank-arms J, to which are pivoted 65 the lower ends of two pitmen, K. The upper ends of the pitmen K are pivoted to the ends of a cross-bar, L, attached to the walking-beam D, at a little distance from its end, so that the cylinder I will be rocked and the 70 plate G moved up and down by the same movement of the said walking-beam D. Several holes are formed through the crank-arms J, to receive the pivot-pins of the pitmen K, so that the said pitmen can be readily adjusted 75 to give a slow movement or a longer and quicker movement to the working-surface of the cylinder I, as the character of the work to be done may require. With this construction, by loosening the cranks J the cylinder I can 80 be adjusted to bring any desired section of its face into working position as the kind of grain to be ground may require.

The grinding-plate G is held forward toward the grinding-cylinder I by a roller, M, journaled in bearings N, which slide in horizontal slots in the frame H, and are held forward by spiral springs O, placed in the outer ends of the said slots, so that the grinding-plate G can move back should a nail, stone, or other hard 85 substance come between it and the cylinder I, and will return to its place as soon as the said substance has passed.

The grain is fed into the space between the plate G and the cylinder I from a hopper, P, 90 supported upon a frame, Q, in front of the frame H.

Having thus fully described our invention, we claim as new and desire to secure by Letters Patent—

1. In a feed-grinder, the combination, with the frame H, and the hopper P and its support, of the reciprocating grinding-plate G, the rocking grinding-cylinder I, the cranks J, 5 and a driving mechanism, substantially as herein shown and described, whereby the grain will be ground as it passes between the said plate and cylinder, as set forth.
2. In a feed-grinder, the combination, with the frame H, the hopper P and its support, the reciprocating grinding-plate G, the rocking

grinding-cylinder I, and the cranks J, of the pitmen F and K, the walking-beam D, and the windmill-pitman B, substantially as herein shown and described, whereby the said feed- 15 grinder will be driven from the said windmill-pitman, as set forth.

ISAAC JAY.
JAMES C. JAY.
